UNITED STATES PATENT OFFICE.

JOHN A. WILSON, JR., OF BUFFALO, NEW YORK, ASSIGNOR TO NOYE MANUFACTURING COMPANY, OF BUFFALO, NEW YORK, A CORPORATION OF NEW YORK.

RADIATOR.

978,975.

Specification of Letters Patent. Patented Dec. 20, 1910.

Application filed October 9, 1909. Serial No. 521,809.

To all whom it may concern:

Be it known that I, JOHN A. WILSON, Jr., a citizen of the United States, residing at Buffalo, in the county of Erie and State of New York, have invented new and useful 5 Improvements in Radiators, of which the following is a specification.

This invention relates to that type of automobile radiators in which the cooling air 10 passes through a plurality of horizontal tubes or cells which are surrounded by the body of water to be cooled.

The object of this invention is to improve the means for separating and supporting the 15 ends of the tubes in a radiator of this character with a view of simplifying the construction and reducing the cost of manufacture.

In the accompanying drawings consisting 20 of 3 sheets: Figure 1 is a front elevation, partly in section, of an automobile radiator embodying my invention. Fig. 2 is a vertical section of the same. Figs. 3 and 4 are fragmentary perspective views, on an enlarged 25 scale, of the preferred form of the radiator, showing a part of the center and a part of the side thereto, respectively. Fig. 5 is a fragmentary front elevation, partly in section on an enlarged scale, of the radiator, 30 shown in Figs. 1-4. Figs. 6 and 7 are vertical sections in lines 6-6 and 7-7, Fig. 5, respectively. Figs. 8 and 9 are fragmentary perspective views showing the modified 35 construction of the tube separating and supporting members. Fig. 10 is a fragmentary perspective view showing another modification of the means for separating and supporting the tubes.

Similar letters of reference indicate corresponding parts throughout the several views.

Referring to Figs. 1-7, A represents the upper tank and B the lower tank of the automobile radiator which are provided respectively with the water inlet *a* and water outlet *b* and which are connected in a well known manner with the cooling system of an engine. C represents a plurality of horizontal parallel tubes which are arranged adjacent to each other between the upper and lower tanks and which are substantially as long as the depth of said tanks. Each of these tubes is preferably quadrangular or square in cross section and of the same diameter and form throughout its length.

The several tubes are separate from each other so as to form water channels, passages or spaces between them, which spaces communicate at their upper and lower ends with the upper and lower tanks A, B. At the front and rear ends of the tubes the same are supported and held apart and the water spaces between the same are closed by the closing means which embody my invention.

In the preferred form of radiator shown in Figs. 1-7, the tubes C are arranged to form vertical and horizontal rows and have their flat sides arranged vertically and horizontally. The separating and supporting means shown in these figures consist of a plurality of round wires D each of which is bent, crimped or corrugated into zig-zag or serpentine form, so as to produce two parallel rows of straight longitudinal sections *d* which are staggered and each of which is arranged opposite the space between two adjacent sections in the other longitudinal row and connected therewith at its ends by cross pieces *d*¹ arranged at right angles to the longitudinal sections. In the manner of assembling the separating wires and tubes, as shown in Figs. 1-7, the cross pieces *d*¹ of the wires are arranged vertically between the horizontal rows of tubes and the longitudinal sections *d* engage alternately with the upper and the lower sides of the tubes. The relative arrangement of the several superposed separating wires is such that each horizontal section *d* bridges the gap or mouth of a corrugation between two adjacent separated horizontal sections *d* of an adjacent wire, so that the several wires together form a screen or skeleton frame the openings of which are of quadrangular form and receive the ends of the tubes. The outer corners of adjacent wires whereby the same engage each other at intervals are provided with beveled faces, as shown at *e*, which permits these wires to be fitted close together and form perfectly square seats between them for the reception of the ends of the tubes. By thus beveling the corners of the separating and supporting wires, it is possible to bring the horizontal sections of adjacent wires into alinement and also the vertical sections of adjacent wires into alinement, thereby causing the rows of tubes to be arranged in straight rows both horizontally and vertically and improving the appearance of the radiator accordingly. It

will also be noted that in this means of separating and supporting the tubes the wires are all in the same vertical plane, thereby producing an even finish of the radiator on the outer ends of the tubes which would not be the case if the wires crossed or extended over each other.

As shown in Figs. 1-7, the separating wires are made round in cross section but it is obvious that the same may be constructed of flat or ribbon wires or strips D¹, as shown in Figs. 8 and 9 or of any other desired cross section.

The spaces between the outermost tiers of tubes at the sides of the radiator are closed by walls f or other suitable means.

After the tanks, tubes, wires and side walls have been assembled in the manner described, the front and rear sides of the radiator are dipped into a solder bath so as to firmly connect the separating wires, tubes, tanks and side walls and form a water tight joint between them.

Instead of constructing the separating members or wires so as to form two parallel rows of longitudinal sections and intermediate cross sections, as shown in Figs. 1-9, the same effect may be produced by bending the separating wire D² so as to form a plurality of sections d² which are arranged at right angles to each other and which incline successively in opposite directions relatively to the length of the wire. When a plurality of such wires are placed side by side with their corners in engagement with each other, an open work frame is produced having a plurality of square openings or seats which receive the ends of the tubes C¹. In order to permit of fitting these wires closely to the tubes, the corners of the wires are provided with beveled faces e¹, as shown in Fig. 10, the beveled faces of adjacent corners abutting against each other and permitting of forming square openings between the assembled wires for the reception of the ends of the tubes. The tubes and separating wires shown in Fig. 10 are secured to each other and a tight joint is produced between the same by means of a solder bath in the manner described with reference to the structure shown in Figs. 1-7. This means of separating the tubes permits of readily and quickly assembling the parts at low cost and without liability of leakage, thereby overcoming the objection to many of the radiators heretofore in use.

I claim as my invention:

1. A radiator comprising a plurality of tubes arranged parallel with each other, and means for separating and supporting said tubes comprising a plurality of wires each of which is crimped or corrugated transversely to the length of the tubes, and the several wires being arranged in the same plane and engaging with each other at inter-

vals forming between them openings which receive the ends of said tubes and holding the latter apart from each other.

2. A radiator comprising a plurality of quadrangular tubes arranged parallel with each other and means for separating and supporting said tubes comprising a plurality of wires each of which is crimped or corrugated transversely to the length of the tubes, to form straight sections which are arranged at right angles to one another, the several wires being arranged in the same plane and engaging with each other at intervals forming openings which receive the ends of said tubes and holding the latter apart from each other.

3. A radiator comprising a plurality of quadrangular tubes arranged parallel with each other, and means for separating and supporting said tubes comprising a plurality of wires each of which is crimped or corrugated transversely to the length of the tubes, to form straight sections which are arranged at right angles to one another, the several wires being arranged in the same plane and having beveled faces at the outer sides of their corners which engage with each other forming together openings which receive the ends of said tubes and holding the latter apart from each other.

4. A radiator comprising a plurality of quadrangular tubes arranged parallel with each other, and means for separating and supporting said tubes comprising a plurality of wires each of which is crimped or corrugated transversely to the length of the tubes, to form two parallel rows of straight longitudinal sections which are staggered so that each section in one longitudinal row is opposite a space between two sections in the other longitudinal row, and transverse sections connecting the corresponding ends of the sections in both longitudinal rows, each longitudinal section of one wire extending across the mouth between two longitudinal sections of another wire forming together a plurality of openings which receive the ends of the tubes and holding the latter apart from each other.

5. A radiator comprising a plurality of quadrangular tubes arranged parallel with each other, and means for separating and supporting said tubes comprising a plurality of wires each of which is crimped or corrugated transversely to the length of the tubes, to form two parallel rows of straight longitudinal sections which are staggered so that each section in one longitudinal row is opposite a space between two sections in the other longitudinal row, and transverse sections connecting the corresponding ends of the sections in both longitudinal rows, each longitudinal section of one wire extending across the mouth between two longitudinal sections of another wire forming together a

plurality of openings which receive the ends of the tubes and holding the latter apart from each other, the outer corners of each wire being beveled and adapted to engage with the correspondingly beveled corners of the adjacent wires.

6. A radiator comprising a plurality of quadrangular tubes arranged parallel with each other, and means for separating and supporting said tubes comprising a plurality of wires each of which is crimped or corrugated transversely to the length of the tubes, to form two parallel rows of straight longitudinal sections which are staggered so that each section in one longitudinal row is opposite a space between two sections in the other longitudinal row, and transverse sections connecting the corresponding ends of the sections in both longitudinal rows, each longitudinal section of one wire extending across the mouth between two longitudinal sections of another wire forming together a plurality of openings which receive the ends of the tubes and holding the latter apart from each other and each row of longitudinal sections of one wire being in line with a row of longitudinal sections in an adjacent wire.

7. A radiator comprising a plurality of quadrangular tubes arranged parallel with

each other, and means for separating and supporting said tubes comprising a plurality of wires each of which is crimped or corrugated transversely to the length of the tubes, to form two parallel rows of straight longitudinal sections which are staggered so that each section in one longitudinal row is opposite a space between two sections in the other longitudinal row, and transverse sections connecting the corresponding ends of the sections in both longitudinal rows; each longitudinal section of one wire extending across the mouth between two longitudinal sections of another wire forming together a plurality of openings which receive the ends of the tubes and holding the latter apart from each other, the outer corners of each wire being beveled and adapted to engage with the correspondingly beveled corners of the adjacent wires and each row of longitudinal sections of one wire being in line with a row of longitudinal sections in an adjacent wire.

Witness my hand this 7th day of October, 1909.
